UNITED STATES PATENT OFFICE.

KARL E. OSSIAN JANSSON, OF FLUSHING, NEW YORK, ASSIGNOR, BY MESNE ASSIGNMENTS, TO STANDARD PLUNGER ELEVATOR COMPANY, OF WORCESTER, MASSACHUSETTS, A CORPORATION OF MASSACHUSETTS.

HYDRAULIC PLUNGER-ELEVATOR.

1,136,678.

Specification of Letters Patent. Patented Apr. 20, 1915.

Application filed April 27, 1908, Serial No. 429,355. Renewed October 16, 1914. Serial No. 867,038.

To all whom it may concern:

Be it known that I, KARL E. OSSIAN JANSSON, a citizen of the United States, residing at Flushing, in the county of Queens and 5 State of New York, have invented certain new and useful Improvements in Hydraulic Plunger-Elevators, of which the following is a full, clear, and exact specification.

This invention relates to hydraulic plunger elevators, and has particular reference 10 to the provision of means located within the main operating cylinder itself for automatically retarding the movement of the elevator at the respective ends of its travel, independently of the controlling valve, whereby 15 the usual automatic valve actuating connections located in the hatchway may be dispensed with.

The invention furthermore has reference 20 to means for automatically checking the respective movements of the car and counterweight at the bottoms of their travel, whereby to distribute the checking strains throughout the system, instead of depending entirely on a few parts acting at a distance 25 from the main cylinder.

By means of this invention, a hydraulic plunger elevator system is provided wherein the plunger automatically throttles the supply to stop the ascent of the car, and its 30 movement toward the lower end of the cylinder is automatically checked by a device within the main cylinder, thus effectually checking or stopping the movements at both 35 ends. To supplement these plunger checking devices, secondary pneumatic hydraulic buffers are provided, controlled by the car and counterweight respectively, whereby the car will be brought to rest without shock at 40 both ends.

The invention further comprises an improved form of plunger bottom whereby the use of rollers, springs or other resilient devices adapted to bear on the interior of the 45 cylinder may be obviated, consisting in the use of glass shoes on the plunger at the points where it may contact with the cylinders.

In the accompanying drawings, Figure 1 50 shows a complete elevator system embodying the invention; Fig. 2 shows on an enlarged scale, the mechanism for cushioning the fall of the counterweight; Fig. 3 shows on an enlarged scale the upper end of the main cyl-

der, and also the mechanism carried by the 55 car for cushioning the fall at the lower end of its movement; Fig. 4 shows on an enlarged scale the end of the plunger; Fig. 5 shows a detail view of a fluid checking cylinder employed in connection with the cushioning of the car at the bottom; Fig. 6 is a detail view of the plunger bottom.

1 represents an elevator car sliding between suitable guides and mounted on a plunger 2 which reciprocates in a cylinder 3.

4 is a counterweight connected with the car 1 and through it to the plunger 2 by cables 5 running over sheave 6.

7 represents a change valve which is controlled through a pilot valve, not shown, by 70 cables 8 and a lever 9 on the car.

10 is a supply tank connected with the main valve 7 by pipe 11, and 12 is an exhaust tank connected with the main valve by 75 pipe 13.

According to this invention, the main cylinder has separate inlet and exhaust ports, which are respectively connected with the main valve 7 by pipes 14 and 15 connected preferably at opposite sides of the cylinder. 80 Also there is connected between the exhaust tank 12 and the exhaust pipe 15 a by-pass pipe 17 containing a check valve 18 opening toward the main cylinder, in order to permit a flow from the exhaust tank to the cylinder 85 in case the plunger "bounds" or runs away from the water in going up causing a vacuum in the main cylinder. The devices for initially checking the movements of the car at top and bottom are contained within 90 the main cylinder, acting in conjunction with the lower end of the plunger, while the secondary checking apparatus for controlling the movements of the car at the bottom is carried by the upper end of the plunger or 95 the car itself acting in conjunction with a buffer mechanism, and the secondary checking apparatus for controlling the movement of the car at the top is carried in part by the counterweight and in part located at the bottom of the shaft, so as to come into operation 100 when the counterweight is within a few feet of the lower end of its travel. In both instances, these auxiliary or secondary checking devices act in combination with the initial checking apparatus within the main cylinder.

Fig. 4 shows on an enlarged scale the

lower end of the main cylinder 3, and the plunger checking devices at the bottom thereof. Mounted within the main cylinder 3 at the lower end is a stationary upright 5 ram 20 composed of a plurality of sections secured together by a rod 21 and tapering to a point at 22. This stationary ram 20 is centered within the lower section of the cylinder casing 3 and held therein by metal 23 10 poured around it, the lower section of the ram being likewise tapered so that it can be gripped and pulled out in case of necessity. 25 represents the lower end of the main plunger 2, which is externally tapered as at 15 26, for checking the upward movement of the plunger, and internally hollowed and tapered as at 27, for checking the movement of the main plunger at the lower end in conjunction with the stationary ram 20. It will 20 be seen that the water trapped in the lower end of the plunger will be forced out between the sides and the ram 20, as the plunger approaches the bottom. It is not intended that the ram 20 shall closely fit the cone 25 27 in the end of the plunger, but the fit grows closer as the plunger approaches the lower end of its movement. The lower end of the plunger is provided with guide projections 28 composed of glass, these projections 30 28 being arranged in two sets one above the other, and staggered with respect to each other, so that the projections of one set or the other will always bear on the inside of the cylinder when the plunger is deflected. The glass shoes 28 have enlarged 35 bases, as 66, and pass through slots in a ring 67 screwed on to the lower end of the plunger, which ring is locked by collar 29. Glass has a particular advantage for this purpose, 40 inasmuch as it will not wear away, and by reason of the large area and staggered arrangement, will not cut the cylinder. At the lower end of the plunger is provided a collar 29 carrying an interior floating ring 30, 45 which ring is permitted to move eccentrically within the collar 29. The interior diameter of the ring and its movement are so calculated that the hole in the ring will always be over the point of the ram 20, so that when the plunger is descending the point of the ram will pass through the hole in the ring and thus it will be insured that the end of the plunger will not strike the end 50 of the ram. At the same time the interior diameter of the ring forms the requisite escape passage for the water trapped in the hollow end of the plunger to produce the proper retardation. The intention of this invention is that the ram will commence to 55 act considerably before the plunger reaches its lower limit, to retard the movement of the car, and after the initial retardation has been produced by the ram, a second retardation is produced by means carried under the 60 car platform in conjunction with hydraulic 65

buffers located adjacent the top of the main cylinder. This mechanism is shown in Fig. 3, wherein 32 represents a drum carried by the platform of the car and surrounding the main plunger 2. 34, 34 represent buffer cylinders containing plungers 35 connected by a yoke 36, through which yoke, plunger 2 slides. Carried by the yoke 36 is a tube 37 connected at its upper end with a piston 38, which works within the drum 32. 75

The operation thus far described is that the drum 32 carried by the car passes over the piston 38, and when the air pressure between piston 38 and the head of the drum reaches a sufficient amount, the piston 38 80 moves downward carrying with it the yoke 36 and forcing the plungers 35 down into the respective cylinders 34. These cylinders 34 are connected by pipe 39 to a fluid retarder 40. The fluid retarder 40 consists of a number of stationary rings 41 through which a number of movable cone shaped plungers 42 sliding on a common rod 43, are forced by the water pressure in pipe 39, there being restricted passages between the plungers 42 and the stationary rings 41. In this manner, the secondary checking effect is produced directly on the car, whereby the whole apparatus will be brought to rest without overstraining any of the parts. 90 95

44 is a small tank connected with pipe 39 through a check valve which opens outwardly from the tank. The object of the tank is to supply sufficient head of water to lift the plungers 35 when the car goes up thereby restoring the plungers 35 and the piston 38 to their initial position. It may be stated that the weight of plungers 42 causes them to fall and open up the passages as soon as the pressure due to the retardation of the car is removed from the pipe 39. 100 105

In order to check the movement of the car at the top of the hatchway, the lower external coned portion 26 of the plunger is caused to automatically cut off or throttle the supply pressure, as the car approaches the top of the hatchway. In order to enable the ascent of the car to be stopped by causing the plunger to automatically throttle the supply pressure, it is desirable that means be provided whereby the car may be started downward without any delay when the exhaust is opened, and this is accomplished herein by providing the main cylinder with separate supply and exhaust passages at the upper end, both communicating with the lower portion of the cylinder, and thereby the throttling of the supply in stopping the car going up does not prevent the exhaust from being freely opened when the car is to come down. To this end, the upper end of the main cylinder comprises an outer section 49 and an inner section 45 within which latter section the main plunger 2 operates. The supply pipe 14 is connected to the pipe 110 115 120 125 130

45, and the exhaust pipe 15 to the pipe 49. The pipe 45 is connected at the top with the cylinder head 46, and so is the pipe 49, while the lower end of pipe 45 is connected with 5 a coupling 47 carried by the upper end of the pipe 3 and the space between pipes 49 and 45 communicates with the interior pipe 3 through a passage or ports 48. The cone portion 26 of the main plunger 2 commences to throttle the supply as soon as it passes within the lower end of pipe 45, and the throttling effect of course increases as the coned portion 26 passes upward within the 10 pipe 45. It will be seen that at a predetermined time, the coned portion 26 can completely cut off the supply to cylinder 3 through pipe 45 if desired, thereby stopping the car since the exhaust valve is of course closed if the supply valve is open. When 15 the car is to descend, the exhaust is opened through the passage 48, without slowing up the initial descent of the car. It is intended that the initial checking effect during the ascent of the car shall be by the cone 26 20 and the cylinder 45, and to produce a secondary checking effect by a buffer mechanism acting to cushion the counterweight and bottom it. To this end, the counterweight 4 carries a yoke 50 connected with a 25 second yoke 51 by a pair of cylinders 52, 52, and working within these cylinders are a pair of rams or plungers 53, 53 carried by a piston 54 working in a cylinder 55. As will 30 appear from Fig. 2, the cylinder 55 has a wide portion containing the restoring spring 56, and a second portion 57 which will contain oil or other fluid. The lower end of the piston 54 carries an extension 58 having 35 grooves 59 therein, and as the counterweight 40 descends, it forces the piston 54 down against spring 56 and forces the oil in cylinder 57 up through the grooves 59. At the same time, the plungers 53 have packings 60 45 at their upper ends, and the air trapped above these packings is forced out through a valve 61, which may be set to produce the desired cushioning effect. In this manner, the fall of the counterweight will be automatically cushioned by a pneumatic hydraulic apparatus, and as the counterweight 50 stops, the movement of the car stops because the latter is commonly underbalanced by the counterweight.

From the foregoing description, it will be 55 seen that I have provided an automatic end stop mechanism for hydraulic elevators wherein the initial checking movement at the ends is applied to the plunger by hydraulic means within the main cylinder, and 60 that a secondary checking movement at the respective ends is applied to the car and to the counterweight by pneumatic hydraulic checking means. By this mechanism, the car will come to rest gently at the ends without 65 shock, and the chances of the failure of the

apparatus to work are very much reduced. In case the end stopping apparatus in the main cylinder should itself fail, the devices on the car and counterweight would operate at the respective ends, and if the latter 70 failed, the car would still be checked by the apparatus within the cylinder.

Modifications and changes in the specific apparatus herein described can be made 75 without departing from the scope of the invention which is not to be limited to the precise arrangement and construction herein described.

Having thus described my invention, I declare that what I claim as new and desire to 80 secure by Letters Patent, is,—

1. The combination with a hydraulic plunger elevator comprising a cylinder having means at the top for supplying and exhausting water, and a plunger working therein, of 85 means wholly within and respectively at the top and bottom of the cylinder for stopping the plunger at corresponding ends of its travel, and means comprising separate supply and exhaust connections with the cylinder 90 whereby actuating pressure for a normal start in one direction may be applied to the plunger independently of one end stopping means, and an exhaust for a normal start in the other direction secured independently of the other end stopping means. 95

2. The combination with a hydraulic plunger elevator, of a main cylinder having separate supply and exhaust ports, and means whereby the plunger automatically cuts off 100 the supply within the main cylinder at the upper end independently of the exhaust.

3. The combination with a hydraulic plunger elevator, of a main cylinder, and means whereby the plunger automatically cuts off 105 the supply within the main cylinder at the upper end.

4. The combination with a hydraulic plunger elevator, of a main cylinder having separate supply and exhaust ports, means whereby the plunger automatically cuts off the supply within the main cylinder at the upper end, and means whereby the car can be started in the reverse direction through said 110 exhaust port.

5. The combination with a hydraulic plunger elevator cylinder and a plunger working therein, of means wholly within the cylinder whereby the plunger automatically cuts off the supply to stop at one end. 115

6. The combination with a hydraulic plunger elevator cylinder and a plunger working therein, of means wholly within the cylinder, whereby the incoming water under supply pressure automatically opposes movement of 120 the plunger at a predetermined portion of its travel.

7. The combination with a hydraulic plunger elevator cylinder and a plunger working therein having portions of two diameters, of 125

- means wholly within the cylinder whereby the working pressure is effective on one diameter and the other diameter becomes effective at a predetermined portion of the 5 stroke to oppose the working pressure and thereby check the movement.
8. The combination with a hydraulic plunger elevator cylinder and a plunger working therein, of means whereby the plunger 10 moves against the supply pressure at a predetermined portion of its travel to exert a checking force thereon, and means for exerting a secondary checking action thereon.
9. The combination with a hydraulic plunger elevator cylinder and a plunger working 15 therein, of means for admitting supply pressure to move the plunger in one direction, and cooperating means wholly within the cylinder and carried by the plunger whereby 20 at a predetermined portion of said stroke the supply pressure is caused to oppose continued movement of said plunger.
10. The combination with a hydraulic plunger elevator cylinder, of a plunger 25 working therein, a counterweight connected with the plunger, means for admitting supply pressure to move the plunger in one direction, means whereby at a predetermined portion of said stroke the supply pressure is 30 caused to oppose continued movement of said plunger, and means for checking the counterweight whereby to increase the checking effect of the supply pressure on said plunger.
11. The combination with a hydraulic cylinder and an element moving therein, of means for admitting supply pressure to move said element in at least one direction, and means carried by the plunger and 35 wholly within the cylinder whereby at a predetermined portion of said stroke the supply pressure is caused to oppose continued movement of said element.
12. The combination with a hydraulic plunger and cylinder, of means within and 40 at one end of the cylinder for checking the movement of the plunger as it approaches that end, and means connected with the plunger outside of the cylinder acting to 45 exert a checking effect on the other end of the plunger whereby to relieve it from excessive strain during the checking movement.
13. The combination with a hydraulic plunger, a working cylinder, and a car and counterweight, of means for automatically 50 checking the plunger at the end of the stroke comprising a plurality of devices acting upon different portions of the plunger, one tending to cause a compression on the plunger and the other an opposing tension, whereby excessive strain on the plunger in 55 stopping is avoided.
14. The combination with a hydraulic plunger elevator system comprising a main 60 cylinder, a plunger and a counterweight, of means within the main cylinder and acting on one portion of the plunger for initially checking the movement, and means separate from the main cylinder acting oppositely on another portion of the plunger for exerting 65 a secondary checking action.
15. The combination with a hydraulic plunger elevator system comprising a main cylinder, a plunger and a counterweight, of 70 a plurality of means within the main cylinder and acting respectively on the ends of the plunger for initially checking the movement, and a plurality of means separate from the main cylinder and acting respectively on the car and the counterweight for exerting opposing checking efforts upon the plunger.
16. The combination with a hydraulic plunger elevator system, comprising a main cylinder, a plunger and a counterweight, of 75 means within the main cylinder for initially checking the movement, and means separate from the main cylinder and acting later than said checking means for exerting a secondary checking action on a different part 80 of the system and opposing the strain caused by said first-named means.
17. In a hydraulic plunger elevator system, comprising a plunger, a main cylinder, a car and a counterweight, the combination therewith of means within the main cylinder for exerting a checking force on the lower end of the plunger to retard the movement of the car at the lower limit, and 85 means outside the cylinder for exerting a second checking force on the upper end of the plunger tending to relieve the compression of said plunger as the car approaches its lower limit.
18. In a hydraulic plunger elevator system comprising a plunger, a main cylinder, a car and a counterweight, the combination therewith of means within the cylinder for exerting a checking force on the plunger 90 at the upper end of its travel, and means for retarding the movement of the counterweight at the lower end of its travel.
19. In a hydraulic plunger elevator system comprising a plunger, a main cylinder, a car and a counterweight, the combination therewith of means within the cylinder for automatically throttling the supply pressure to check the car going up, and means for simultaneously applying a checking force to 95 the counter-weight.
20. The combination with an elevator car, of an automatic lower end stop mechanism comprising a hydraulic cylinder, a plunger 100 therein adapted to be moved by the car as it approaches its lower limit and a hydraulic column connected with said cylinder.
21. The combination with an elevator car, of an automatic lower end stop mechanism comprising a hydraulic cylinder, a plunger 105

- therein adapted to be moved by the car as it approaches its lower limit, a hydraulic column connected with said cylinder and means for retarding the flow of said column.
- 5 22. The combination with a hydraulic plunger elevator cylinder having a pressure inlet and a plunger working therein, of means whereby at a predetermined portion of the pressure operated stroke of the plunger the supply pressure passage is automatically restricted by the plunger.
- 10 23. The combination with a main cylinder, a plunger and a car carried thereby, of a drum carried on the lower side of the car, a piston and cross head mounted to be engaged by said drum before the car reaches its bottom limit, and a hydraulic cylinder and plunger connected with said cross head to be actuated by the pressure on said piston 15 within said drum.
- 20 24. The combination with hydraulic buf-
- fer mechanism comprising a hydraulic cylinder and plunger, of a pneumatic cylinder and plunger for actuating said hydraulic mechanism.
- 25 25. In a hydraulic plunger elevator, the combination with a main cylinder, of a plunger having an enlarged lower end provided with rubbing surfaces of glass.
- 30 26. In a hydraulic plunger elevator comprising a car and a plunger, the combination with a stationary cone, of a floating ring within the lower end of the plunger and having an internal diameter such as to include the point of the cone at all lateral 35 positions of the plunger in the cylinder.

In testimony whereof I affix my signature,
in presence of two witnesses.
